UNITED STATES PATENT OFFICE

165,238

TELEPHONE SUPPORT

William C. O'Brien, Baltimore, Md.

Application November 14, 1949, Serial No. 6,014

Term of patent 7 years

(Cl. D26—14)

To all whom it may concern:

Be it known that I, William C. O'Brien, a citizen of the United States of America, residing at the city of Baltimore, in the State of Maryland, have invented a new, original, and ornamental Design for a Telephone Support, of which the following is a specification, reference being had to the accompanying drawings, forming a part thereof.

Fig. 1 is a sectional view of a telephone support embodying my new design taken on line 1—1 of Fig. 2;

Fig. 2 is a plan view thereof;

Fig. 3 is a fragmentary bottom view of the left-side shown in reduced scale.

I claim:

The ornamental design for a telephone support, substantially as shown and described,

W. C. O'BRIEN.
